Inventor
Stuart Speirs
By his Attorney
Ade Romeville

UNITED STATES PATENT OFFICE.

STUART SPEIRS, OF NEW YORK, N. Y.

SAFETY RAZOR.

Application filed April 20, 1922. Serial No. 555,744.

To all whom it may concern:

Be it known that I, STUART SPEIRS, a citizen of the United States, and resident of the borough of Manhattan, city of New York, in the county of New York and State of New York, have invented certain new and useful Improvements in a Safety Razor, of which the following is a specification.

This invention relates to a safety razor, 10 Its object is the production of a razor that is particularly adapted for women shaving themselves beneath their arms, although it may be used in a manner similar to that of the ordinary safety razor now in use. A 15 second object of the invention is the production of a razor that can be safely employed to shave hollow or concaved surfaces. A third object of the invention is the production of a razor that will curve a straight 20 blade when located in place in the razor, and which will remain curved when in use.

The organization of the invention comprises a longitudinally convexed blade platform and a longitudinally concaved bending 25 and locking member. A straight blade is detachably connected to the locking member, and when the latter is locked to the platform the blade is longitudinally curved to conform to the adjacent faces of the platform 30 and locking member. Lugs are formed with the platform and also with the locking member to cover the ends of the cutting edge 35 of the blade, to avoid injury when shaving the arm pits of a user or other concaved surfaces.

In the accompanying drawings Fig. 1 represents a side elevation of an exemplification 40 of the improved safety razor; Fig. 2 shows a top plan view of Fig. 1; Fig. 3 indicates an enlarged view similar to Fig. 1 and an 45 enlarged section as on the line 3, 3 of Fig. 2; Fig. 4 represents an enlarged front view of the razor with the members thereof in their open position; Fig. 5 is a section of Fig. 4 on the line 5, 5 and Fig. 6 shows a front view of the razor with a modification.

A handle 20 supports the convexed blade platform 21 curved along its longitudinal 50 axis. The platform has formed therewith the tooth guard 22 and the protecting lugs 23 at its lower end corners. At the outer end of the platform 21 is formed the latch opening 24 and from the outer face thereof 55 extend the depressions 25. A concaved blade bending and locking member 30 is

hinged to the platform 21 by means of the hinge 31. The member 30 has formed at its upper edge the flange 32 and its swinging end is provided with the locking latch 33. 60 Protecting lugs 34 are formed at the lower corners of the member 30 and gripping lugs 35 extend from the inner face thereof. The flat cutting blade 36 is indicated with the cutting edge 37, the side edges 38, the lower 65 corners 39 and the top edge 40.

To locate the blade 36 in operative position it is placed upon the concaved face of the member 30 with its side edges 38 snapped under the gripping lugs 35 and the lower 70 corners 39 over the protecting lugs 34.

The bending and locking member 30 is now swung with the blade 36 upon the curved platform 21 and the locking latch 33 is locked in the latch opening 24, and 75 the blade 36 will automatically be curved to conform to the surfaces of the platform 21 and the locking member 30. The corners 39 of the blade 36 will be securely covered by the protecting lugs 23 of the platform 21 80 and the protecting lugs 34 of the locking member 30. The gripping lugs will be seated in the depressions 25.

In Fig. 6 a blade bending and locking member is indicated at 45 with a pair of 85 locking latches 46 similar to 33, which engages latch openings similar to 24 in the curved platform 47. Protecting lugs 48 similar to 34 are provided for the member 45.

The lower edge of the platform 47 is 90 devoid of teeth as shown and its hinge is also dispensed with. The blade is indicated at 50 and its corners are fully covered and protected by the lower portion of the platform 47 and the lugs 48 of the locking 95 member 45.

Various modifications may be made in the invention and the present exemplification is to be taken as illustrative and not limitative thereof.

Having described my invention what I desire to secure by Letters Patent and claim is:

1. In a safety razor the combination of a convex platform curved along its longitudinal axis, a concave bending and locking member curved along its longitudinal axis adapted to be locked to said platform and a blade clamped between the convex face of the platform and concave face of said 105 locking member, said blade locking member provided with a positioning flange on its 110

upper edge and having over hanging gripping lugs to hold the blade in an initially flexed position prior to its locking engagement with the platform.

- 5 2. In a safety razor the combination of a blade platform curved along its longitudinal axis, a handle extending from the platform, a blade bending and locking member curved along its longitudinal axis, pivoted to and 10 adapted to be locked with said platform, a blade initially flexed and locked to the locking member, when the latter is unlocked from the said platform and means to lock the locking member to the said platform, 15 said blade being fully flexed when said locking member is locked to said platform and securely held between said elements.
3. In a safety razor the combination of a convex platform, a concave bending and

locking member pivoted to said platform, 20 means to detachably lock the locking member to the said platform, over hanging gripping lugs extending from the inner face of the locking member and depressions on the inner face of the platform for seating the 25 gripping lugs when the blade bending and locking member is locked to the platform and a straight blade initially flexed and secured to the locking member by means of said gripping lugs, said blade fully bending 30 to the contour of the adjacent faces of said platform and locking member when the latter elements are locked to each other.

Signed at the borough of Manhattan, city of New York, in the county of New York 35 and State of New York, this 17th day of April, A. D. 1922.

STUART SPEIRS.
